UNITED STATES PATENT OFFICE.

SWAN SMITH, OF ST. PAUL, MINNESOTA.

PRINTING-PRESS.

1,314,025.

Specification of Letters Patent. Patented Aug. 26, 1919.

Application filed April 9, 1917. Serial No. 160,598.

To all whom it may concern:

Be it known that I, SWAN SMITH, a citizen of the United States, residing at St. Paul, in the county of Ramsey and State of Minnesota, have invented certain new and useful Improvements in Printing-Presses, of which the following is a specification.

My invention relates to improvements in printing presses of that class in which the cylinder member and sliding type bed are employed, the object of my invention being particularly to provide means for reciprocating the type bed in desired unison with the rotation of the cylinder.

To this end my invention consists in the features of construction and combination hereinafter particularly described and claimed.

Referring to the drawings forming part of this application,

Figure 1 is a side elevation of my improved machine partly broken away,

Fig. 2 is a detail view of a link member showing part of the actuating mechanism for the type bed.

Fig. 3 is a similar view of Fig. 1 showing the side of the machine more broken away and the parts in different position.

Fig. 4 is a detail view of the combined gear and cam forming part of the actuating mechanism, together with a portion of the type bed in coöperation therewith.

Fig. 5 is a view of the parts shown in Fig. 4 taken at right angles to Fig. 4 and

Fig. 6 is an end view of a machine partly broken away.

Referring to the drawings A represents the frame work of a machine upon which is slidably supported in a suitable manner the horizontal type bed B. Said bed preferably rests upon rollers 2 as shown in Fig. 6. Supported in the housing 3 forming an upwardly projecting part of the frame work is the shaft 4 of the cylinder 5.

The operating mechanism for said cylinder forming no part of the present invention is not specifically shown.

The type bed is reciprocated by the following described mechanism. Mounted upon a transverse main shaft 6 journaled in the framework of the machine is a gear wheel 7 formed around a portion of its periphery with teeth 8 which mesh with teeth

9 projecting downwardly from the under side of the type bed.

Also constituting a part of the actuating mechanism for the type bed is an arm 10 having pivotal support 11 in the base of the machine, the arm 10 at its upper end being connected through the medium of a link 11' with one end of an arm 12, the other end of the arm 12 being pivotally connected with the under side of the type bed. The arm 10 is swung upon its pivotal support by means of a lever arm 13 having pivotal connection at one end with the gear wheel 7 adjacent its outer edge and at its opposite end having pivotal connection with the arm 10 below the link 11'.

The link 11' as shown in Figs. 1 and 3 has pivotal connection 14 at its upper end with the arm 12 which is connected with the type bed, and at its lower end has pivotal connection 15 with the upper end of the main actuating arm 10. The link is formed intermediate of its end with an outward extension 16, said extension carrying at its free end an anti-friction roller 17 which projects into a slot 18 in the frame work of the machine.

The slot 18 while extending, as shown, in a horizontal position is as shown partially curved and irregular to constitute an irregular path of travel for the roller 17. The curvature in the guideway or slot is such as to so vary the relative angularity of the link 11', to permit the arm 12 to follow the advancing bed which is controlled by the gear 7 during its engagement therewith, the rate of speed of the bed being controlled solely by the gear when the teeth

are in mesh. When the gear and bed are in contacting relation which is the actual printing stroke the bed is actuated through the gear directly from the shaft 6, the arms 13, 10 and 12 and the link 11' simply moving in unison with the gear and bed. When however the gear and bed are disengaged (Fig. 1), or in other words the control of the bed is transferred to the lever mechanism, the arm 13 has not yet reached dead

center, relative to its point of attachment on the arm 10. The bed thereafter moves by momentum, the arm 12 being now in tension to arrest the movement of the bed, the roller 17 rolling on the downwardly curved lower wall of the slot 18, presenting resistance to

the movement of the bed while the arm 13 is crossing dead center, thus affording a gradual arrest of the forward movement of the bed. As soon as the arm 13 has crossed 5 dead center it is placed in compression thereby transmitting the power in the shaft 6 to the arm 10, which in connection with the link 11' and arm 12 returns the bed.

The same action as hereinbefore explained 10 occurs at the other end of the slot 18, the slot serving only, during gear and rack engagement as a guide to direct the roller 17 into the end curved portion of the slot, so that the teeth of the gear and rack will always be in meshing relation at the time of 15 transfer from the lever mechanism to the gear.

The cylinder as shown in Fig. 6 also carries at one end teeth 19 which intermesh 20 with teeth 20 upon the upper side of the type bed to assist in moving the type bed in one direction while the cylinder is in lowered position. By suitable mechanism, not shown, the cylinder is raised so as not to 25 interfere with the return of the type bed.

As will be evident, the lever connections with the type bed operatively effect the movement of the type bed simultaneously with the gear wheel while the gear teeth 30 mesh with the type bed.

The link 11', together with the slot 18 synchronizes the action of the levers with the direct action of the gear upon the type bed, and thus the operation of the bed by the 35 gear wheel does not interfere with the levers.

As the type bed passes out of meshing relationship with the teeth of the gear wheel, as indicated in Fig. 1, the levers alone will continue the movement of the type bed to 40 the end of its travel and then return the type bed to meshing relationship with the teeth of the gear wheel. The same action takes place when the type bed passes out of meshing relationship with the teeth of the 45 gear wheel at the opposite end of travel of the type bed.

I claim:

1. A type printing press of the class described comprising a framework and type bed supported thereby, a driving shaft and wheel supported upon said shaft, an arm having fulcrum support in the frame a lever arm connecting the free end of said power arm with said type bed, a lever arm connecting said power arm with the rim of said wheel and means permitting a compensating movement between the lever arm connected with said wheel and a lever arm connected with said type bed.

2. A printing press of the class described comprising a framework, a type bed slidably supported thereby, a driving shaft and wheel supported upon said shaft, a power arm having fulcrum support in the frame, lever connection between said power lever

and wheel, and lever connection between said power lever and type bed and a compensating member constituting synchronism adjustment between the lever arm connected with the movement of said wheel and bed, 70 the lever arm connected with said type bed, and an irregularly extending guideway for said compensating member.

3. A printing press of the class described comprising a framework type bed slidably supported thereby, a driving shaft and wheel supported upon said shaft and having teeth intermeshing with the teeth carried by said type bed, a power lever arm having fulcrum support in said frame and 75 connection between said power arm and wheel, connection between said power arm and type bed and means for synchronizing an uneven movement of said power arm imparted thereto from said wheel with an 80 uneven movement of the type bed.

4. A printing press of the class described comprising a framework and type bed slidably supported thereby a driving shaft and wheel supported upon said shaft a power 90 arm having fulcrum support in the frame, a lever arm connecting said power arm and a type bed and intermediate link between said power arm and type bed lever and an irregular extending guideway for said link. 95

5. A printing press of the class described comprising a framework a type bed slidably supported thereby, a driving shaft and cylinder supported upon said shaft, a power arm having fulcrum support in the frame, 100 a lever arm connecting said power arm and the rim of said cylinder, a lever arm connected with the under side of said type bed, a link member connecting said power arm and said type bed lever arm with the 105 irregular extending guideway for said link member and independent positive driving connection between said cylinder and type bed.

6. A printing press of the class described, 110 comprising framework, a type bed slidably supported thereby, a driving shaft and gear wheel supported upon said shaft, meshing gear connection between said wheel and type bed during a part of the rotation of said wheel, lever mechanism operatively connected with said wheel and said type bed, compensating means included within said lever mechanism for synchronizing the movement of said lever mechanism with the 115 movement of said gear wheel and said type bed when the teeth of said gear and bed are in mesh, said lever mechanism acting upon said type bed after the type bed is 120 carried out of mesh with said gear wheel to continue the movement of the type bed and return the same into meshing engagement with said wheel.

7. A printing press of the class described, comprising framework, a type bed slidably 130

supported thereby, a driving shaft and wheel supported upon said shaft, meshing connection between said wheel and type bed during a part of the rotation of said 5 wheel, a lever mechanism operatively connected with said type bed, means for actuating said lever mechanism in synchronization with said gear and for actuating said lever mechanism after said type bed is car-

ried out of engagement with said gear to 10 continue the movement of said type bed and to return it into engagement with said gear.

In testimony whereof I affix my signature in presence of two witnesses.

SWAN SMITH.
